UNITED STATES PATENT OFFICE

JOHN WICKS, OF OAK PARK, ILLINOIS, ASSIGNOR TO AUTOMATIC ELECTRIC, INC., OF CHICAGO, ILLINOIS, A CORPORATION OF DELAWARE

AUTOMATIC TELEPHONE SYSTEM

Original application filed May 6, 1920, Serial No. 379,217. Divided and this application filed December 11, 1925. Serial No. 74,679.

My invention relates in general to automatic telephone systems, but is concerned more particularly with the provision of an improved connector circuit for use in applying a semiselective ringing scheme to an automatic system.

There are various other features disclosed, but not claimed, these other features being covered by Wicks Patent No. 1,586,057, issued May 25, 1926, and a second Wicks Patent No. 1,631,351, issued June 7, 1927. The present application is a division of the said first mentioned patent.

Referring to the drawings, comprising Figs. 1, 2, 3, and 4, I have shown therein by means of the usual circuit diagrams the apparatus required to establish a complete connection from a toll line terminating in jack J, Fig. 1, to a local subscriber's station A, Fig. 4. This apparatus comprises the cord circuit O, Fig. 1, located at a toll operator's position in a toll switching station or office; the two conductor trunk line extending from jack J' in the toll switching office to the toll first selector D, Fig. 2, in a main exchange of the system; the toll transmission repeater E; the toll second selector F, Fig. 3; and the combination toll and regulator connector H, Fig. 4. The repeater, second selector, and connector mentioned are in the same office or exchange as the toll first selector D, which as indicated above may be one of the main offices or exchanges of a large multi-office system. In addition to the above I have also shown means common to all the trunk lines extending from the toll switching office to the local office, and which is used to collect or refund deposited coins at any subscriber's station, such as station A with which it may be connected via the toll service trunking system. This additional means or apparatus comprises the special cord circuit O', Fig. 1, which special cord circuits may be supplied in quantities of one or two per position; the trunk line extending from jack J² in the toll switching office to the local office; and the special connector M, Fig. 2, in which the said trunk line terminates and which has access to all the toll first selectors such as the selector D.

In view of the well known character of the apparatus and the descriptions thereof in the publications previously referred to, I will not describe such apparatus in detail in the present application, but will proceed at once to explain the operation of the circuits with a view to pointing out the new improvements. For this purpose it will be assumed that the subscriber at substation A, Fig. 4, has placed a long distance call with a toll recording operator and that the ticket containing the usual data concerning the desired connection has been forwarded to the toll operator having the cord circuit O, Fig. 1, for completion.

Having extended a connection to the desired distant exchange over one of her toll lines, as for example the toll line which terminates in jack J, Fig. 1, and having ordered the proper local line to be connected up in that exchange, the toll operator will next proceed to call the subscriber at substation A by way of the toll service trunking system. Observing that the toll service trunk terminating in jack J' is idle, as indicated by the unlighted condition of the busy lamp L³, the operator will insert the calling plug of cord circuit O in the said jack J', the double throw listening and calling device K² being thrown to calling position at the same time. Upon the insertion of the plug in the jack J' a circuit is completed for relays 20 and 21 in series; and the latter relay, upon energizing, lights the busy lamp L³ at its armature 23, establishes a locking circuit for itself at its armature 24, and at its armature 25 prepares a circuit whereby relay 22 may later be bridged across the trunk conductors 30 and 31, this circuit being open for the time being, however, at armature 26 of relay 20, which relay pulls up in series with relay 21. It is understood that the outgoing trunk jacks and lamps are multiplied at other operators' positions in the usual manner, and the multiple busy lamps at the other positions are, of course, lighted in parallel with lamp L³.

The key K² being in calling position, as before stated, the operator's head set, including the calling device S in series therewith, will

be bridged across the upper and lower strands of the cord circuit, resulting in the closure of a circuit for the line relay 51 of the toll selector D over the trunk conductors 30 and 31 in series. Upon the completion of this circuit the line relay 51 is energized and closes the circuit of the slow acting release relay 52. Upon energizing, the latter relay prepares the selector switch for operation in its vertical movement in the usual manner.

The toll operator will now operate her calling device S in accordance with the telephone number of the subscriber at substation A. When the calling device dial is operated in accordance with the first digit of the number, a series of interruptions is produced in the circuit of the line relay 51 of the toll selector D. The line relay 51 is, therefore, deenergized a plurality of times corresponding to the digit called, and at each deenergization sends a current impulse through the slow acting series relay 53 and the vertical magnet 56 to battery. By the operation of the vertical magnet the switch shaft is raised step by step until the wipers 70-73, inclusive, stand opposite the horizontal level of bank contacts which are terminals of trunk lines leading to the desired thousand group. The slow acting relay 53 is energized in series with the vertical magnet, maintaining its armature continuously attracted during the vertical operation of the switch, and at the first upward movement of the switch shaft closes a circuit for the stepping relay 54. Upon energizing, relay 54 establishes a locking circuit for itself at its upper armature and at its lower armature prepares a circuit for the rotary magnet 57. At the end of the vertical movement of the switch, the slow acting relay 53 is deenergized and completes the aforesaid circuit for the rotary magnet, which is accordingly energized and advances the wipers 70-73, inclusive, into engagement with the first set of bank contacts in the level opposite which they were raised. Near the end of its stroke the rotary magnet breaks the locking circuit of the stepping relay 54, which is accordingly deenergized to open the circuit of the rotary magnet. Both the rotary magnet 57 and the stepping relay 54 having deenergized, the operation now depends upon whether the test contact with which the test wiper 71 is in engagement is busy or is not busy. If this test contact is busy, it will have a ground potential upon it and a circuit will be established by way of the said test wiper, whereby the stepping relay 54 is again energized to again close the circuit of the rotary magnet 57, which in turn operates to advance the switch wipers into engagement with the next set of bank contacts. This operation continues as long as the test wiper 71 continues to engage grounded test contacts. As soon as the first non-grounded test contact is reached, which we will assume to be the test contact 75 asso-

ciated with the trunk line extending to the repeater E, the stepping relay 54 will not again be energized, and the rotary movement of the switch will cease. The switching relay 50, which heretofore has been short circuited, is now energized over the following circuit: Grounded conductor 58, winding of the switching relay 50, off normal springs 59 and the winding of the stepping relay 54 to battery. Relay 50 is of such high resistance that the stepping relay 54 is not energized. Upon energizing, relay 50 connects the grounded conductor 58 to the test wiper 71 at armature 61; opens the circuit of the release magnet 55 at its armature 62; and at its armatures 60 and 64 disconnects the incoming trunk line conductors 30 and 31 from the windings of the line relay 61 and extends them by way of wipers 70 and 73, bank contacts 74 and 77, left hand windings of the repeating coil R, and normally closed contacts of the relay 101 to the upper and lower windings, respectively, of the line relay 104 of the toll transmission repeater E. The line relay 104 is accordingly energized and closes a circuit for the slow acting release relay 105 which, upon energizing in turn, closes the talking conductors through the repeater by means of its armatures 115 and 118, and also at its armature 116 completes a holding circuit in the usual manner which extends by way of conductor 144 back to the selector D where it serves to maintain the switching relay 50 energized throughout the connection. Ground potential is also placed on the multiples of test contact 75 by means of this circuit in order to make the selected trunk busy to other selectors.

When the line relay 104 of the repeater E was energized as previously explained, a control or operating circuit extending to the line relay 151 of the toll second selector F, Fig. 3, was completed as follows: Ground at G⁵, armature 126 and its working contact, conductor 143, armature 160 and its resting contact, and the winding of the line relay 151 to battery. Upon the closure of the above circuit, the line relay 151 is energized, and completes a circuit for the slow acting release relay 152 in the usual manner. Upon energizing, relay 152 grounds the release trunk conductor 144 locally at its upper armature, and at its lower armature prepares the circuits of the selector for the vertical operation thereof.

The toll operator may now operate the dial of her calling device S in accordance with the second digit in the number of the subscriber at substation A. The interruptions produced by this operation are repeated by the line relay 104 of the repeater E, which relay causes a series of deenergizations of the line relay 151 of the selector F. While the line relay 104 is repeating impulses to the line relay 151 it also sends a series of im-

pulses through the slow acting relay 106, which operates to disconnect the A. C. relay 121 and also to short circuit the lower right hand winding of the repeating coil R. These operations render the control circuits more efficient. The toll second selector F is very similar to the selector D and its operation, therefore, will not be described in detail. It will be sufficient to say that the deenergizations of the line relay 151 bring about the operation of the vertical magnet 156 through the medium of which the switch shaft is raised step by step until the wipers 170-173, inclusive, stand opposite the horizontal level 15 of bank contacts which are terminals of trunk lines leading to the desired group of connector switches. The slow acting relay 153 is energized in series with the vertical magnet and at the first upward step of the shaft 20 closes the initial energizing circuit of the stepping relay 154 by way of the off normal contact springs 159. The stepping relay 154 locks itself as usual and prepares a circuit for the rotary magnet 157. At the end of the 25 vertical movement of the switch, the slow acting relay 153 is deenergized and the switch wipers are rotated in search of an idle trunk line by means of the rotary magnet 157, which is controlled by the stepping relay 154 and the test wiper 171. When the 30 idle trunk line is reached, which we will assume to be the trunk line comprising conductors 178-181, inclusive, the rotation of the switch will cease, leaving the wipers 170-173, 35 inclusive, in engagement with bank contacts 174-177, inclusive. The switching relay 150 is now energized and at its armatures 161 and 163 connects the talking conductors 141 and 145 with the line wipers 170 and 173, respectively. Relay 150 also extends conductors 142 and 143 by way of its armature 162 and 160, wipers 171 and 172, and bank contacts 175 and 176 to conductors 179 and 180. The conductor 143 is included in 40 the control circuit of the toll selector F, and when it is extended as above mentioned, the line relay 151 and the release relay 152 of the selector are, of course, deenergized, the selector being maintained in operated position by the continued energization of the switching relay 150, which is supplied with ground over the conductor 144 coming from the repeater E.

The switch control circuit having been extended, as above stated, to the conductor 180, it may be further traced by way of the said conductor 180, the upper winding of the relay 204 of the combination connector H, Fig. 4, contact springs controlled by the back bridge relay 200, and the upper winding of the line relay 201 to battery. Upon the extension of the control circuit over the above path, the lines relay 201 is energized and completes a circuit for the slow acting release relay 202, which at its armature 216 prepares

the connector for vertical operation in the usual manner. At its upper armature 218, relay 202 connects ground G^s with the release trunk conductor 305, which conductor extends to and is multiplied in the banks of the second selectors of the regular exchange trunking system which have access to the combination toll and regular connector H. Conductor 305 is the release trunk conductor of the trunk line comprising conductors 304, 305, and 306 which terminates in bank contacts 301, 302, and 303, respectively, Fig. 3. These bank contacts are assumed to be located in the banks of one of the regular selectors referred to, and the ground potential upon conductor 305, and the test contact 302 and its multiples, render the connector H busy. 70

A branch of the conductor 305 may be traced from junction point 306' by way of conductor 305', winding of relay 207, conductor 179, bank contact 175, wiper 171, armature 162 and its working contact, conductor 142, armature 128 and its resting contact, and the resistance 111 to battery. By current flow over the above circuit the relay 207 is energized and at its armatures 236 and 237 prepares circuits for the ring cutoff relay 205 which will be explained later. Relay 207 85

also closes a circuit for the switching relay 204 by means of its armature 238, and the latter relay, upon energizing, produces a number of circuit changes in the connector which are brought about for the purpose of enabling it to function as a toll connector rather than as a regular connector. These circuit changes 90

include the opening of the permanent locking circuit of the ring cutoff relay 205 at armature 225, the shifting of the locking circuit of the busy test relay 206 at armature 224, the disconnection of the regular trunk line conductors 304 and 306 at armatures 223 and 226, and the preparation of a supervisory signaling circuit for the toll operator at armature 223. These circuit changes and 95

the results effected, thereby will be mentioned more in detail hereinafter. Before proceeding further with the explanation a few more details concerning relays 207 and 204 may be inserted with benefit. Relay 207 is of relatively low resistance, and the circuit traced 100 through its winding from the grounded conductor 305 to the conductor 179 and test contact 175 places a potential upon the said test contact 175 and its multiples, which is sufficiently near to ground potential to render the connector H busy to the toll second selectors. 105

With regard to relay 204, the upper winding of this relay, which is included in the circuit of line relay 201, is of low resistance and is not necessarily strong enough to energize the relay by itself, but is strong enough to hold the said relay in operated position after it has been completely operated by the closure of the circuit through its lower winding. In order to reduce the impedance of the upper 110

winding so as not to interfere with operating impulses transmitted to the line relay 201, the relay 204 is provided with a copper slug as indicated in the drawing.

5 The connector H is now ready to be operated under the control of the calling device S, when the dial is actuated in accordance with the next digit in the number of the subscriber at the substation A. A series of interruptions is produced as before, which are repeated by the relay 104 of the repeater E to bring about a series of deenergizations of the line relay 201. At each deenergization the line relay 201 transmits a current impulse through the vertical magnet 210 over the following circuit: Ground at G⁷, armature 215 and its resting contact, armature 216 and its working contact, off normal springs 222 and 220, winding of the slow acting series relay 203, and winding of the vertical magnet 210 to battery. This is the circuit over which the first impulse is transmitted. At the first upward step of the switch shaft, however, the off normal springs are shifted, and the circuit extends from the working contact of armature 216 by way of off normal springs 222 and 221, armature 217 and its working contact, (relay 203 being now energized), winding of the relay 203, and the winding of the vertical magnet 210 to battery. By the operation of the vertical magnet the switch shaft is raised step by step until the wipers 270-272, inclusive, stand opposite the level of bank contacts in which the line of substation A is terminated. The slow acting relay 203 which is energized in series with the vertical magnet, maintains its armature attracted throughout the vertical operation of the switch. When this relay energizes at the beginning 40 of the vertical movement it closes the following circuit for the ring cutoff relay 205: Ground at G⁸, armature 218 and its working contact, armature 219 and its working contact, working contact of armature 237 and the said armature, and the lower winding of 45 the ring cutoff relay 205 to battery. Upon energizing, relay 205 opens contacts included in a later established signaling circuit at its armatures 227 and 229, and at its armature 228 establishes a locking circuit for itself as follows: Grounded conductors 305', working contact of armature 228 and the said armature 236 and its working contact, and the lower winding of relay 205 to battery. At the end 50 of the vertical movement of the switch, the slow acting relay 203 deenergizes and prepares the connector for operation in its rotary movement.

60 The tool operator may now operate the dial of the calling device S in accordance with the final digit in the number of the subscriber at substation A. The interruptions produced are repeated as before through the medium of relay 104, and cause another series 65 of deenergizations of the line relay 201 of the

connector H. At each deenergization, the line relay 201 now sends a current impulse through the rotary magnet 212 over the following path: Ground at G⁷, armature 215 and its resting contact, armature 216 and its working contact, off normal springs 222 and 221, armature 217 and its resting contact, resting contact of armature 233 and the said armature, armature 246 and its resting contact, and the winding of the rotary magnet 212 to battery. In response to these impulses the rotary magnet operates to rotate the wipers 270-272, inclusive, into engagement with the particular set of bank contacts in which the line of substation A terminates, these bank contacts being the contacts indicated in the drawing by the reference characters 273, 274, and 275. The slow acting relay 208 is energized in parallel with the rotary magnet and retains its armatures attracted throughout 70 the rotary movement of the switch. At its armature 239, relay 208 connects the test wiper 271 to the winding of the busy test relay 206, and at its armature 240, relay 208 closes a shunt around armature 233 of relay 206 and 75 its resting contact to guard against the possibility of the said relay being momentarily energized while the test wiper 271 is passing over busy test contacts. In order to afford an opportunity to explain the operation of the 80 busy test circuits it will be assumed that when the line of substation A is called at this time it is busy. In such case the test contact 274 will be grounded and when the test wiper 271 makes connection with the said test contact, the test relay 206 will be energized, the circuit being traceable as follows: Grounded test contact 274, test wiper 271, contact springs controlled by armature 244 of relay 209, armature 239 and its working contact, 85 armature 243 and its resting contact, and the winding of the test relay 206 to battery. The test relay is energized over the above circuit and when the slow acting relay 208 deenergizes at the end of the rotary movement of the 90 switch, the test relay becomes locked up by means of the following circuit: Grounded test contact 274, test wiper 271, working contact of armature 224 and the said armature, working contact of armature 230 and the said armature, contact springs controlled by armature 239 of relay 208, armature 243 and its 95 resting contact, and the winding of the test relay 206 to battery. The various circuit changes effected by the operation of the test 100 relay will now be briefly pointed out. Its locking circuit which is closed at armature 230 has just been explained. At armature 231 the circuit of the switching relay 209 is 105 opened, at armature 232 a shunt is connected around the armature 236 of relay 207 and its working contact in order to prevent 110 accidental deenergization of the ring cutoff relay 205 (by movement of ringing key at the operator's cord circuit), at armature 233 the 115 120 125 130

circuit of the rotary magnet 212 is opened in order to prevent the switch wipers from being rotated off the contacts of the called line, and at armature 235 a lead from the busy signaling machine Q is connected to the lower line conductor 181. The conductor 181 extends back through the selector F to the lower right hand winding of the repeating coil and it follows that the toll operator will be given 5 an audible busy signal indicating to her that the called line is busy. This busy signaling operation is similar to methods in common use, and will be understood without further explanation.

10 The toll operator will now restore her listening key K² and may proceed to work on other connections while waiting for the line of substation A to become idle, first, however, removing the plug from jack J in order to 15 prevent the busy tone from passing out over the toll line. When key K² is restored the supervisory relay 6 is connected in bridge of the trunk conductors 30 and 31 in place of the operator's head set and this relay 6 would be 20 energized in series with the line relay 104 of the repeater E were it not for the fact that the connector H is waiting on a busy line. In order to make this clear a circuit will be traced which was completed by the busy test 25 relay 206 and which extends as follows: Ground at G¹⁰, resting contact of armature 241 and the said armature, armature 234 and its working contact, working contact of armature 223 and the said armature, conductor 30 30 178, bank contact 174, wiper 170, working contact of armature 161 and the said armature, conductor 141, armature 123 and its resting contact, armature 115 and its working contact, upper right hand winding re- 35 peating coil R, and the winding of relay 100 to battery. Current flow in the above circuit serves to operate relay 100 which closes a circuit for the relay 101. Upon energizing, the latter relay disconnects the incoming 40 45 trunk line conductors from the windings of the line relay 104 and at the same time closes a local circuit for the upper winding of the said line relay. The exchange battery is thus entirely disconnected from the trunk line and it will be evident, accordingly, that the supervisory relay 6 will not be energized and the lamp L² will not be lighted.

50 When the line substation A becomes idle, ground potential is removed from the test contact 274 and the locking circuit of the test relay 206 is broken. The test relay, therefore, deenergizes, disconnects the busy signaling machine Q, opens the circuit of relay 100 at the repeater E, and establishes a circuit for 55 the switching relay 209 which may be traced as follows: Grounded conductor 305', resting contact and armature 231, upper winding of the switching relay 209, resting contact of armature 239 and the said armature, contact 60 springs controlled by armature 244, test wiper

271, test contact 274, winding of the switching relay 317 of the individual line switch C, and the winding of the stepping magnet 318 to battery. Upon the closure of the above circuit relays 209 and 317 are energized in series, and the latter relay is operated to disconnect the line conductors 320 and 321 from their normal connections in the line switch. Relay 317 is not completely operated because of the fact that the line relay of the line switch has not been energized, and does not connect the line conductor with the wipers of the line switch. In the connector H, the relay 209, upon energizing, opens the circuit of the rotary magnet 212 at armature 246, establishes 70 a locking circuit for itself at armature 245, connects ground G¹¹ to the test wiper 271 at armature 244, thus closing the circuit of the switching relay 317 of the line switch over a new path excluding the upper winding of relay 209 which was formerly included in the circuit, and at armatures 242 and 247 closes the talking conductors through to the line wipers 270 and 272.

75 The connection has now been established with the line of substation A. When the busy test relay 206 is deenergized and the connector cuts through on to the called line as described in the preceding paragraph, the circuit of relay 100 at the repeater is broken as previously stated, and this relay and also relay 101 are deenergized. The incoming trunk conductors are thereby connected again to the windings of the line relay 104 and current is supplied to the bridged supervisory relay 6 80 at the operator's cord circuit. Relay 6 is, therefore energized and lights the supervisory lamp L² to advise the operator that the called line has become idle and that connection thereto has been completed.

85 90 95 100 105 110 115 120 125 130 The next operation is to ring the subscriber at substation A. For this purpose the operator throws the key K³ momentarily to ringing position, thereby projecting ringing current out over the trunk line with which the cord circuit O is connected, to operate the alternating current relay 121 at repeater E. Upon attracting its armature 128, relay 121 breaks the previously described circuit of the relay 207 at the connector H. Relay 207 accordingly deenergizes and at its armature 236 breaks the locking circuit of the ring cut off relay 205. Relay 205 then deenergizes and at its armatures 227 and 229 opens the talking conductors and establishes the usual signaling circuit which includes the ringing current generator Gen and its own upper winding. There is no special novelty in the signaling circuit itself, although it is believed that the provision of a pick up relay, which is rendered necessary by the fact that semi-selective ringing is used, is new in an automatic system of this kind. As shown herein, the line of substation A is a party line, substation A being a so called "two bell" station while sub-

station A' is a one bell station. The operations following the deenergization of the ring cutoff relay 205 may be explained more in detail as follows: When relay 205 falls back, a circuit is prepared at its armature 281 for the "pick up" relay 282, and as soon as the pick up common conductor 285 becomes grounded during a silent period the said circuit is closed. Upon energizing, relay 282 locks itself at its armature 283, and at its armature 284 finally closes the signaling circuit, after which the bell at substation A will be rung automatically as long as the receiver remains on the hook. During the ringing operation the operator is given the well known "ringing current induction", provided, of course, that she is listening on the line, to notify her that the ringing is proceeding satisfactorily. This is accomplished by means of the inductive path which extends from armature 247 of relay 209 by way of the low capacity condenser 299 to the resting contact of armature 235 of relay 206. Condenser 299 is of very low capacity, preferably about .005 microfarads, and permits just enough ringing current to leak back in the direction of the operator to give her an easily distinguished signal.

When the subscriber at substation A removes his receiver in response to the ringing of his bell the ring cutoff relay 205 will be operated by current from the exchange battery in series with the ringing current generator Gen, or by current from the exchange battery in series with the booster battery associated with the generator, and upon attracting its armature 228 will reestablish its former locking circuit, the operator having restored her ringing key by this time to permit the energization of relay 207. The ring cutoff relay also disconnects its own upper winding and the ringing apparatus at its armatures 227 and 229, respectively, and closes the talking conductors at these same armatures.

The transmitter at substation A is now supplied with talking battery through the winding of the battery feed relay 100 at the repeater E. This circuit will not be traced in detail, but it will be observed that the lower line conductor extends uninterruptedly back through the connector H and the selector F to the lower right hand winding of the repeating coil R, whence it extends through the resistance 113 to ground, while the upper line conductor 320 extends back through the connector H and the selector F to the upper right hand winding of the repeating coil R, from which point it may be traced through the said winding and through the winding of the relay 100 to battery. Relay 100 is energized by current flow through the transmitter at substation A, and upon attracting its armature closes the circuit of relay 101, which again operates to close a local circuit for line relay 104, and breaks the circuit of the supervisory

relay 6 at the operator's cord circuit, thus causing this relay to deenergize and extinguish the supervisory lamp L². The completion of the local circuit for the line relay, it will be noted, removes the release of the connection from the control of the operator. 70

The operator will now come in on the line again by throwing her key K² to listening position, and after ascertaining that the proper person is at the telephone, will request such person to deposit the correct coin or coins to pay for his connection. When the coins are deposited the operator is given an audible signal over the telephone circuit in the usual manner so that she will know that the right amount has been deposited, and also the polarized magnet of the paystation is connected to the line in order that the operator may thereafter either collect or refund the coins. 75

Everything is now in readiness for conversation to begin, at least so far as the connection to the party at substation A is concerned. Assuming that the desired party has been obtained in the distant exchange, the operator will now complete the connection at her cord circuit and the connected parties can converse as desired. It will be observed that the connection includes a two conductor trunk line from the toll switching station to the main or local exchange (the trunk comprising conductors 30 and 31), which is a decided economy over the former arrangements requiring at least three and sometimes even four conductor trunk lines. Another advantage which may be pointed out is found in the arrangement by which the called subscriber controls the release of the connection, while his receiver is off, through the medium of relays 100 and 101, the latter of which controls a local circuit for the line relay 104. This arrangement makes it possible for the toll operator to change cord circuits after a called party has answered without releasing the established connection. 100

When the connection is finished both subscribers will hang up their receivers. Upon the replacement of the receiver at substation A, relays 100 and 101 at the repeater E are deenergized and the line relay 104 is again connected across the conductors of the incoming trunk line. As a result the supervisory relay 6 at the operator's cord circuit is energized and the lamp L² is lighted to give the operator a disconnect signal. Before releasing the connection the operator will have to collect whatever coins were deposited, and this operation will now be explained. 110

The trunk line extending from jack J² in the toll switching station to the connector M in the local exchange and comprising conductors 351, 352, and 353 is one of a limited number of similar trunks which are used exclusively for collecting and refunding operations. Any one of these trunks may be made use of to collect or refund at any subscriber's 125 130

station in the local exchange in question which has been connected with via the toll service trunking system. When the toll operator gets ready to collect, then, on the connection just described, she will insert the plug of special cord circuit O' in the jack of an idle collect trunk, and we will assume that the trunk line shown in the drawing is the one taken for use. When the plug is inserted in jack J² a circuit is completed over the sleeve of the jack which includes the calling device S' and the relay 350 in series. Upon energizing, relay 350 lights the busy lamp L⁴ and its multiple lamps at other positions (not shown), and also closes a circuit over trunk conductor 352 which includes the line relay 360 of the connector M at the distant local exchange. Upon energizing relay 360 closes a circuit for the slow acting release relay 361 which upon energizing in turn prepares the circuit of the vertical magnet at its lower armature in the usual manner. Relay 361 also closes a circuit through the upper or polarizing winding of the electro-polarized relay 364.

The operator will now operate the calling device S' in accordance with the number of the toll service trunk line in use in the connection for which it is desired to collect, it being understood that all the toll service trunks extending to the local exchange in question are numbered consecutively in accordance with the bank numbering of the connector M and associated connectors. Assuming that connector H is a one hundred line switch, it may have access to one hundred toll service trunks numbered from 01 to 99. To proceed, when the calling device S' is operated in accordance with the first digit of the number, the relay 350 is deenergized a plurality of times, causing a like plurality of deenergizations of the line relay 360 of the connector M. The latter relay controls the connector M in substantially the same way that the line relay 201 controls the combination connector H and on that account the explanation will not be given in detail. Briefly, at each deenergization, line relay 360 sends a current impulse through the vertical magnet 367 which operates to raise the switch shaft step by step until the wipers 370, 371, and 372 stand opposite the level in which is terminated the branch line which is a multiple of the particular toll service trunk to be collected over. The slow acting series relay 362 is energized in series with the vertical magnet, maintains the vertical magnet circuit intact after the off normal springs have shifted at the first upward step of the shaft, and at the end of the vertical movement deenergizes and shifts the operating circuit to the rotary magnet 368.

When the calling device S' is operated in accordance with the next and last digit in the number, the line relay 360 sends a series of

current impulses to the rotary magnet 368 which in response thereto operates to rotate the wipers 370-372, inclusive, until they come to rest in engagement with the bank contacts 373-375, inclusive. At the first rotary step the rotary off normal springs 369, which are included in the rotary magnet circuit, are separated, but the magnet circuit is maintained closed by the slow acting series relay 363 until the last rotary impulse is received after which the said relay deenergizes and the magnet circuit is opened.

An independent connection has now been established with the toll service trunk by way of the collect trunk and the connector M. While the toll operator is operating the dial of calling device S' to establish the branch connection she has her listening key K² in the cord circuit O in operated position and as soon, therefore, as the connector M establishes connection with the branch comprising conductors 30', 300, and 31', and the slow acting relay 363 has deenergized, the operator is given an audible high frequency tone which notifies her that she has connected with the proper toll service trunk. This tone signal is provided to prevent any error in collecting which might arise due to faulty manipulation of the calling device or faulty operation of the connector M, either of which would cause connection to be established with some other toll service trunk than the one over which it is desired to collect. If the operator does not hear the tone she will know that something is wrong and will call the number over again. The manner in which the tone signal is placed on the trunk line will be easily understood. It will be noted that the lower wiper 372 of the connector M is connected to the lower terminal of the grounded secondary winding of the induction coil associated with high frequency generator Gen', while the upper wiper 370 is connected to ground through a condenser. With this arrangement when connection is established with the bank contacts 373-375, inclusive, the secondary of the induction coil is bridged across the branch conductors 30' and 31', resulting in the transmission of an audible signal to the operator as stated.

Having perceived the O. K. signal, the operator will immediately operate the collect key in the cord circuit O'. By this operation the exchange battery at the toll switching station is bridged across the trunk conductors 351 and 353 and a flow of current is produced in the winding of relay 365 and the lower winding of the electropolarized relay 364, these relays being bridged across conductors 351 and 353 at the connector M. When this current flow is established, relay 364 is not operated, due to the opposition of its polarizing winding; but relay 365 is operated and closes the following circuit: From the positive pole of grounded battery B², through the resist-

ance lamp in series therewith, resting contact of armature 381 and the said armature, armature 382 and its working contact, winding of marginal relay 366, wiper 371, bank contact 374, conductor 300, armature 63 and its working contact, wiper 72, bank contact 76, conductor 130, winding of relay 107, and the high resistance 109 to ground. Current flow in the above circuit operates relay 107, the relay 366 remaining inoperative due to the high resistance of relay 107 and resistance 109. Upon energizing, relay 107 closes a circuit for relay 108 which, upon attracting its armatures 123 and 124, opens the heavy talking conductors at the repeater E and connects conductors 141 and 145 to conductor 130. A relatively low resistance branch path to ground is thus established which is in parallel with the relay 107 and resistance 109 and which may be traced readily by way of conductors 141, 178, and 320 to the substation A, whence the circuit extends through the polarized magnet of the paystation mechanism to ground. Battery B² is a high voltage battery and produces a current flow in the above traced branch circuit which is in the proper direction to operate the polarized magnet to collect the deposited coin or coins, the paystation mechanism being reset at the same time. When the branch circuit through the polarized magnet is established the resulting current flow is sufficient to operate the marginal relay 366 and this relay upon attracting its armature 383 substitutes an interrupted tone signal for the continuous tone signal, thereby advising the toll operator that the collect circuits are all right and that presumably the coins have been collected. The collect key is now restored and relay 365 is thereby deenergized, whereupon the battery B² is disconnected and relays 366, 107, and 108 are deenergized. Also, since the paystation mechanism at substation A has been reset by the polarized magnet, when the battery B² is disconnected and the polarized magnet is thereby permitted to restore its armature the said magnet is disconnected from the line. The toll operator will now operate her collect key once more, thereby again connecting battery B² to the line of substation A as before described. This time, however, since the polarized magnet at the paystation has been disconnected the marginal relay 366 will not be operated and the operator will not get the interrupted tone back on the line. By this the operator knows that the collecting operation has been successful and she will again restore the collect key.

If the operator desires to refund a deposited coin rather than collect it she may do so by operating the refund key instead of the collect key. Assuming the same circuit conditions to exist as in the previous case, where the operator collected the coins, if the refund key is operated the exchange battery is connected

in bridge of trunk conductors 351 and 353 as before, except that it is reversed, and as a result the electro-polarized relay 364 at the connector M is operated as well as the relay 365. It follows that battery B' will be connected to the line of substation A instead of battery B², and battery B' being of the opposite polarity, the deposited coins are refunded instead of collected. Except as pointed out, the refunding operation is the same as the collecting operation, and the operator is given supervision by means of the interrupted tone in the same way.

The special collect trunks are used only for collecting or refunding, which takes but a few seconds, and are at once restored to common use. When the plug is removed from jack J² relay 350 is deenergized and breaks the circuit of the line relay 360 of the conductor M. Relays 360 and 361 are thereupon deenergized and the switch is restored to normal by means of the release magnet 385 in the usual manner.

The release of the main connection over the toll service trunks is also brought about by the removal of the plug from the jack, at least this is true if the called subscriber has replaced his receiver. In order to explain this fully, it will be assumed that the plug is removed from jack J' before the subscriber at substation A has hung up. By the removal of the plug the circuit of relay 20 is broken and this relay is deenergized, but relay 21 remains locked up. The busy lamp L³ and its multiples are thus kept lighted to indicate that the trunk is busy. It will be noticed also that relay 21 maintains a test potential on the sleeve of jack J, which permits the usual audible busy test circuits to be used in the operator's cord circuits if desired. Now when the called subscriber hangs up his receiver relays 100 and 101 at the repeater R are deenergized and the line relay 104 is connected across the incoming trunk conductors as explained heretofore in considering the control of the supervision. The effect of this is to energize the slow acting relay 22 which was bridged across the trunk conductors 30 and 31 by the deenergization of relay 20. Upon energizing, relay 22 breaks the locking circuit of relay 21, and this latter relay, upon deenergizing, disconnects relay 22 from in bridge of the trunk. Relays 22 and 104 are, therefore, deenergized. The latter relay breaks the circuit of the slow acting release relay 105 and also breaks the operating circuit extending to the connector H. By the latter operation relays 201 and 202 are deenergized and the connector H is restored by means of release magnet 213 in the usual manner.

When the relay 105 at the repeater E deenergizes it removes ground from the conductor 144, thereby permitting the switching relays 50 and 150 of selectors D and F, respectively, to deenergize. Thereupon these switches are restored by means of their re-

spective release magnets 55 and 155 and all the apparatus will have been returned to normal position.

The description of the improved toll service trunking system is now believed to be complete; at least all the various features which have to do with the invention are believed to have been covered. It is true that the operations of the combination toll and regular connector H when used by a local subscriber rather than a toll operator have not been gone into, but these operations have no especial connection with the present invention, and, besides, they have already been described in certain of my prior applications previously referred to; therefore it is believed to be unnecessary to go into such further details now.

What is claimed is:

1. In a telephone system, a party line, a series of automatic switches including a final connector switch for extending a connection to said line, a common code ringing machine and a plurality of common generator leads extending therefrom, a source of ringing current, means in said ringing machine for connecting said source to said leads at intervals in accordance with different codes, a pick up relay in said connector for connecting one of said leads to the connected called line to signal a desired station thereon, and a circuit for said relay controlled by said ringing machine and effective to energize said relay only while the said generator leads are disconnected from said source of ringing current.

2. In a telephone system, connectors, a called party line, a plurality of branches of said line accessible from the connectors, code signaling mechanism for applying signaling current to the called line in a predetermined series of alternate live and dead periods, automatically applied means for causing the signaling current to be applied to the called line only at the starting of the first live period of the next series responsive to the operation of a connector in effecting connective relation with the called line regardless of the time said operation occurs, and automatically applied means for causing a specific said code series of signaling current to be applied to the called line in correspondence with the branch of the called line a connector is operated into connective relation with so that a different code series of signaling current will be applied to the called line depending upon what branch of the called line is connected with.

3. In an automatic telephone system, automatic connectors, a called party line, a plurality of branches of said line accessible from the connectors, code signaling mechanism for applying signaling current to the called line in a predetermined series of alternate live and dead periods, automatically applied means for causing signaling current to be applied to the called line only at the starting of the first live period of the next series re-

sponsive to the operation of a said connector in effecting connective relation with the called line regardless of the time said operation occurs, and automatically applied means for causing a specific said code series of signaling current to be applied to the called line in correspondence with the branch of the called line a said connector is operated into connective relation with so that a different code series of signaling current will be applied to the called line depending upon what branch of the called line is connected with.

4. In a telephone system, a connector switch, a called line, a current interrupter having means included in a signaling current path of the connector for controlling the application of signaling current from the connector to the connected called line in successive trains of series, automatically applied means made operative solely responsive to effecting the connection to the called line for causing said application of signaling current to be initiated, and means controlled by the said interrupter whereby the application of any portion of a said train of series will be disabled from being initially through the connector after the interrupter has started the application of a train.

5. In a telephone system, a plurality of connector switches, called lines, a current interrupter having means included in a multiplied signaling current path, each path including one of said connectors, the said interrupter for controlling the application of signaling current from a connector to its connected called line in successive trains of series, automatically applied means made operative solely responsive to effecting the connection to the called line for causing said application of signalling current to be initiated, and means controlled by the said interrupter whereby the application of any portion of a said train of series will be disabled from being initially applied through a said connector to its connected called line after the interrupter has started the application of a train.

6. In a telephone system, a plurality of connector switches, called lines, a current interrupter having means included in a multiplied signaling current path, each path including one of said connectors, the said interrupter for controlling the application of signalling current from a connector to its connected called line in successive trains of series, means whereby the said interrupter will independently control the application of current from each of the said plurality of connectors, automatically applied means made operative solely responsive to effecting the connection to the called line for causing said application of signaling current to be initiated, means controlled by the said interrupter whereby the application of any portion of a said train of series will be disabled

from being initially applied through a said connector to its connected called line after the interrupter has started the application of a train without effecting the application of current from other of said connectors controlled by the interrupter, and means which will enable the signalling current to be applied over the said disabled connector at the initiation of the next succeeding train thereafter.

7. In an automatic telephone system, an automatic connector switch, a called line, a current interrupter having means included in a signalling current path of the connector for controlling the application of signalling current from the connector to the connected called line in successive trains of series, automatically applied means made operative solely responsive to effecting the connection to the called line for causing said application of signalling current to be initiated, and means controlled by the said interrupter whereby the application of any portion of a said train of series will be disabled from being initially applied through the connector after the interrupter has started the application of a train.

8. In an automatic telephone system, an automatic connector switch, a called line, a current interrupter having means included in a signalling current path of the connector for controlling the application of signalling current from the connector to the connected called line in successive trains of series, automatically applied means made operative solely responsive to effecting the connection to the called line for causing said application of signalling current to be initiated, and means controlled by the said interrupter whereby the application of any portion of a said train of series will be disabled from being initially applied through the connector after the interrupter has started the application of a train but will be enabled to apply the next succeeding train thereafter.

9. In a telephone system, a connector, a called line accessible from the connector, signalling mechanism for applying signalling current to the called line in a series of alternate live and dead periods, and automatically applied means for causing the signalling current to be applied to the called line only at the starting of the next live period responsive to the operation of the connector in effecting connective relation with the called line regardless of the time said operation occurs.

10. In a telephone system, a connector, a called line accessible from the connector, code signalling mechanism for applying signalling current to the called line in a predetermined series of alternate live and dead periods, means for preventing the initial application of signalling current to the called line intermediate of a said series, and automatically

applied means for causing the signalling current to be applied to the called line only at the starting of the first live period of the next series responsive to the operation of the connector in effecting connective relation with the called line regardless of the time said operation occurs.

In witness whereof, I hereunto subscribe my name this 8th day of December, A. D. 1925.

JOHN WICKS.
